UNITED STATES PATENT OFFICE.

SUMNER B. SARGENT, OF LOS ANGELES, CALIFORNIA.

PUMP-PLUNGER ROTOR.

Application filed April 14, 1922. Serial No. 552,730.

To all whom it may concern:

Be it known that I, SUMNER B. SARGENT, a citizen of the United States, residing at Los Angeles, in the county of Los Angeles and State of California, have invented a new and useful Pump-Plunger Rotor, of which the following is a specification.

This invention relates to pumping equipment for oil wells, and relates particularly to means for preserving an equal wear upon the pump barrel, the pump plunger, and the reciprocating parts of oil pumping equipment, as well as overcoming difficulties arising from sucker rods becoming disconnected and the sanding up of the working parts of the pump.

It is common practice in pumping oil from wells, to employ a closely fitting cylindrical steel plunger which reciprocates in a steel barrel. In these pumps a preponderance of wear generally occurs upon one side of the barrel, thus causing an elongated cross-section to result instead of preserving a true circular cross-section by an equal distribution of wear over the entire surfaces of the barrel and the plunger. It will be seen that the confinement of the wear to any certain portion of the barrel soon creates a space between the barrel and the plunger through which a leakage of oil may occur, and it will be further seen that such a condition impairs the efficiency of the pump in a much shorter time than if the wear were equally distributed. Also, when it is desired to re-establish the efficiency of the pump, the barrel and the plunger must be lifted from the well and a new liner inserted in the barrel. The removal of a pump barrel entails a considerable expenditure in both labor and expense, and also the loss of production while the pump is out of operation.

Another difficulty arising in the pumping of oil from wells is that sucker rods become unscrewed, this generally occurring at some point in the well between the surface and the pump, and necessitating fishing for the loose end of the line of sucker rods and drawing same to the surface in order that connection may again be properly made.

It is an object of my invention to provide a means for rotating the plunger of a pump within the barrel as the plunger is reciprocated, so that an equal distribution of wear will be maintained, and thereby making it possible to restore the efficiency

of the pump by replacing the worn plunger with an oversize plunger without the necessity of removing the barrel from the well.

It is also an object of my invention to provide a means whereby a rotative force will be exerted upon the line of sucker rods in a direction to keep the joints between the sucker rods screwed together.

It is a still further object of my invention to provide an improved means for adjusting the amount of rotation imparted to the sucker rods and plunger at each reciprocation thereof.

Other objects and advantages will be made evident hereinafter.

Referring to the drawing which is for illustrative purposes only:

Fig. 1 is a somewhat diagrammatic fragmentary elevation showing an oil well pump equipped with my device.

Fig. 2 is a sectional view taken on a plane represented by the line 2—2 of Fig. 1.

Fig. 3 is a vertical section through Fig. 2.

Fig. 4 is a fragmentary view showing a rotation regulating device sometimes desirable of employment upon the device shown in the preceding figures.

Fig. 5 is a plan view similar to Fig. 2, showing a form of my invention adapted to rotate the sucker rods and the plunger during both the up and the down strokes thereof.

Fig. 6 is a vertical section through Fig. 5.

Fig. 7 is a view showing a resilient operating link which may be used in the practice of my invention.

Fig. 8 is a view showing a pressure released device which it may be desirable to use with a parallel link for reciprocating the bell crank.

In Fig. 1 of the drawing a line of tubing 11 is shown, having a pump barrel 12 attached to its lower end. Within the pump barrel 12 a plunger 13 is adapted to be vertically reciprocated by a line of sucker rods 14 which are connected through a polished rod 15 and a stirrup 18 with a reciprocating element such as the walking beam 19. As shown in Figures 2 and 3, the lower ends 20 of the stirrup 18 support the yoke 21 which in turn supports the rotating mechanism 22.

The yoke 21 has a central enlargement 24 surmounted by a projection 25 having the formation of a horizontal disk, and the polish rod 15 is extended through a hole 26

provided therefor through the yoke 21 and the projection 25. A head 28 is clamped upon the polished rod 15 above the yoke 21 and serves to transfer the weight of the line 5 of sucker rods and the plunger to the projection 25 upon which it rests.

Surrounding the lower portion of the head 28, a driving plate 30 which is circular in shape, rests upon the top surface of the projection 25, and has upwardly projecting therefrom a circular flange 31 which is inferiorly formed to receive the hexagonal lower end 32 of the head 28. Adjacent to both the top and bottom faces of the plate 15 30 I place fiber rings 33 which are clamped thereagainst by a ratchet wheel 35 and a plate 36 which is of slightly greater diameter than the ratchet wheel and has mounted thereupon a driving ring 37. The 20 ratchet wheel 35 and the plate 36 are compressed together with a pressure of sufficient intensity to give the desired driving function between the members 35 and 36 and the plate 30 by springs 38 compressed by 25 bolts 34.

A bell crank 39 is mounted upon one end of the yoke 21, this bell crank having a lateral arm 40 and a vertical arm 41. The arm 40 of the bell crank is maintained in a position substantially parallel to the walking beam 19 by a parallel link 43, as shown in Fig. 1, while the arm 41 thereof engages, as illustrated in Fig. 7, a recess 44 provided in the periphery of the driving ring 37. From 30 Fig. 1 it will be perceived that as the walking beam reciprocates the pumping apparatus connected thereto, the arm 40 of the bell crank 39 will be partially rotated back and forth between the positions indicated by the 35 dotted lines 45 and 46. This reciprocal movement is transferred through the arm 41 to the ring 37 and provides a means for rotating the ratchet wheel 35 by means of a spring retained pawl 48 which engages the 40 teeth 49 of the ratchet wheel whenever the ring 37 is reciprocatively rotated in the direction indicated by the arrow 50 in Fig. 2. I also provide a stop pawl 51 for preventing the counter rotation of the ratchet 45 wheel. This pawl 51 is mounted upon a member 52 rigidly secured upon the yoke 21, and is maintained against the teeth 49 of the ratchet wheel by a spring 53.

The frictional drive provided between the 50 ratchet wheel 35 and the driving plate 30 provides for the movement of the ratchet wheel independently of the driving plate 30 when the force required to rotate the plunger 13 exceeds a predetermined amount, 55 thus preventing injury to the equipment. An additional precaution against injury to the equipment when the plunger becomes sanded in the barrel is provided in the novel arrangement of parts which permits the 60 yoke and the driving mechanism sustained

thereupon to slide downwardly upon the polished rod, this being possible owing to the fact that the head 28 rests upon the projection 25 and is free to lift out of engagement with the driving plate 30.

In Fig. 4 I show the improved manner in which I regulate the amount of rotation the plunger shall be given at each reciprocation thereof. A bracket 55 is clamped upon the left arm 56 of the stirrup 18. This bracket 70 55 is provided with a slot 57 having a pin 58 therein which extends downwardly from the bracket to a position adjacent to the inner face 59 of the pawl 48. When the ring 37 reciprocates backward in the direction of the arrow 60, the pawl is lifted from engagement with the teeth 49 by the pin 58. Upon the forward stroke, as indicated by the arrow 61, the pawl cannot engage the teeth until a certain point in the rotation of the ring is reached; thus it is possible to adjust the pin 58 within the slot 57 to provide the engagement of a certain predetermined number of teeth at each reciprocation of the ring 37. The pin 58 may be clamped within 80 the slot by any suitable means.

It is desirable in some installations to provide for the rotation of the plunger during both the upward and downward strokes thereof. This is accomplished as shown in 90 Figures 5 and 6, by placing a second drive ring 64 upon the drive ring 37, this ring 64 being provided with a projecting portion 65 having a recess 61 engaged by the vertical arm 67 of a bell crank 68, which is mounted upon the end of the yoke 21 opposite to the bell crank 39. A spring retained pawl 69 is adapted to rotate the ratchet wheel 35 in the same direction as it is rotated by the 100 pawl 48.

As hereinbefore explained it is evident from Fig. 1 that the arms 40 and 71 of the bell cranks are rotated upwardly through a partial revolution during the down stroke, and downwardly during the up-stroke. When the arm 40 is raised during the downward stroke, the ring 37 is reciprocated in the direction of the arrow 75, the pawl 48 coming into engagement with the teeth 49, and the ratchet wheel thereupon being rotated in a clockwise direction. During the upward stroke, the lateral arms of the bell cranks are revolved downwardly, causing the movement of the ring 37 in a direction opposite to that indicated by the arrow 75, while the ring 64 is reciprocated in the direction of the arrow 76 causing the engagement of the pawl 69 with teeth 49, and the rotation of the ratchet wheel in a clockwise direction again results; this latter rotation being during the upward stroke while the former rotation was accomplished during the downward stroke.

In Fig. 7 I illustrate an alternative means whereby the plunger may not rotate when 130

the frictional resistance between the plunger and the barrel exceeds a certain point. Instead of the rigid link 43 as shown in Fig. 1, a resilient link 78 is connected between the 5 walking beam 19 and the arm 40 of the bell crank 39. A simple and efficient construction of the resilient link 78 consists of a frame composed of plates 79 and 80 having parallel slide rods 81 extending therebetween; a rod 82 extending from the plate 79 and having connection with the arm 40 of the bell crank; a cross head 85 adapted to slide on the rods 81, having a rod 86 extending upwardly therefrom passing 10 through a hole 87 provided in plate 80 and making connection with a pin 88 mounted upon the walking beam 19; and a spring 90 compressed between the plate 80 and the cross head 85, this spring holding the cross-head 15 forcibly against the plate 79, but permitting the link 78 to be extended when a resistance is exerted thereupon through the bell crank.

The movement of the bell crank 39 may 20 be varied to provide different rates of feed of the ratchet plate by moving the pin 88 upon the walking beam 19, either to the right or left in the direction of the indication 92, to change the action of the parallel 25 link.

In Fig. 8 of the drawing I show a releasable device adapted to be incorporated in the parallel link 43 so that when a resistance against rotation due to sanding up 30 of the plunger within the pump barrel is created, the parallel link arrangement will become inoperative so that no further relative stress will be applied to the sucker rod until the condition causing the resistance is 35 overcome and the device replaced in operative condition. When this device is used, the parallel link is provided in two lengths 40 100 and 101; the length 100 connecting between the walking beam 19 and the pivot 45 102 in the upper end of a plate 103 which has another plate 104 pivoted at 105 to its lower end; and the member 101 being connected between the bell crank and a pivot 50 108 in the upper end of the plate 104. A 55 grooved block 110 is mounted upon the plate 103 and a spring member 111, extending from the upper end of the member 104 as shown, engages the grooved block 110 and maintains the plate 104 normally in a position against the plate 103.

It will be perceived that pivot 105 and pivot 108 are not in direct alignment, thus a tendency of plate 104 to swing outwardly as indicated by arrow 112 is created. Under ordinary working conditions, the 60 spring 111 is of sufficient strength to resist the outward swing of plate 104 due to the rotative movement created by the tensile force acting in the parallel link during the 65 upstroke thereof. When a condition arises

causing a resistance against rotation of the polished rod and the members suspended therefrom, the increased rotative movement of the plate 104 upon pivot 105, due to the increased tension in the parallel link members, overcomes the engagement of spring 111 with the grooved block 110 and allows the plate 104 to swing outwardly into the released position indicated by the dotted lines 115. After the release of plate 104, 70 the link arrangement is inoperative as the direct line arrangement necessary for the transfer of the movement of the walking beam to the bell crank is destroyed. 75

I claim as my invention:

1. In a device of the class described, the combination of: a polished rod; a walking beam; a stirrup connecting said walking beam with said polished rod; a ratchet wheel frictionally mounted on said polished rod; pawl means to actuate said ratchet wheel and thereby rotate said polished rod; and means whereby said ratchet wheel may move downward independently of said polished rod. 80

2. In a device of the class described, the combination of: a polished rod; a walking beam; a stirrup connecting said walking beam with said polished rod; a ratchet wheel mounted on said polished rod; pawl 85 means to actuate said ratchet wheel and thereby rotate said polished rod; and means whereby said ratchet wheel may move downward independently of said polished rod. 95

3. In a device of the class described, the combination of: a polished rod, a yoke slidably retained upon said polished rod; means for vertically reciprocating said yoke; a plate rotatably supported upon said yoke; means for rotating said plate; and means rigidly mounted upon said polished rod adapted to be lifted by said yoke and to engage said plate, said rigidly mounted means being disengageable from said plate so that said yoke and said rotatable elements 100 supported thereby may move downward independently of said polished rod. 105

4. In a device of the class described, the combination of: a polished rod; a member slidably retained upon said polished rod; means for vertically reciprocating said slideable member; rotatable means supported by said slideable member; and a head rigidly mounted upon said polished rod adapted to be lifted by said slideable member and to engage said rotatable means, said head being disengageable from said rotatable means so that said rotatable means and said slideable means may move downward independently of said polished rod. 115

5. In a device of the class described, the combination of: a polished rod; a member slidably retained upon said polished rod; means for vertically reciprocating said slideable member; rotatable means supported by 120 125 130

said slideable member; means whereby said rotatable means may rotate said polished rod; and means acting between said slideable member and said polished rod whereby said slideable member may lift said polished rod, said slideable member being adapted to move downward independently of said polished rod.

6. In a device of the class described, the combination of: a polished rod; a ratchet plate frictionally mounted upon said polished rod; a pawl for actuating said ratchet plate; means for reciprocating said pawl; and means for controlling the engagement 10 of said pawl with the teeth of said ratchet wheel.

7. In a device of the class described, the combination of: a polished rod; a yoke slidably retained upon said polished rod; a plate 20 member supported upon said yoke; a ratchet wheel adapted to rotate said plate member; a ring rotatably mounted upon said plate member; a pawl upon said ring adapted to rotate said ratchet wheel; means connecting 25 between said polished rod and said plate member whereby said polished rod may be rotated by said plate member; and means for rotatably reciprocating said ring.

8. In a device of the class described, the combination of: a polished rod; a yoke slidably retained upon said polished rod; a plate member supported upon said yoke; a ratchet wheel frictionally engaging said plate member; a ring rotatably mounted upon said 30 plate member; a pawl upon said ring adapted to rotate said ratchet wheel; means connecting between said polished rod and said plate member whereby said polished rod may be rotated by said plate member; and means for rotatably reciprocating said ring.

9. In a device of the class described, the combination of: a polished rod; a yoke slidably retained upon said polished rod; a plate member supported upon said yoke; a ratchet wheel frictionally engaging said plate member; a ring rotatably mounted upon said plate member; a pawl upon said ring adapted to rotate said ratchet wheel;

means connecting between said polished rod and said plate member whereby said polished rod may be rotated by said plate member; and crank means for rotatably reciprocating said ring.

10. In a device of the class described, the combination of: a polished rod; a yoke slidably retained upon said polished rod; a plate member supported upon said yoke; a ratchet wheel frictionally engaging said plate member; a ring rotatably mounted upon said plate member; a pawl upon said ring adapted to rotate said ratchet wheel; means connecting between said polished rod and said plate member whereby said polished rod may be rotated by said plate member; crank means for rotatably reciprocating said ring; and means for controlling the period of engagement of said pawl with said ratchet.

11. In a device of the class described, the combination of: a polished rod; a head mounted upon said polished rod; yoke means supporting said head; reciprocative mechanism for rotating said head; a crank for reciprocating said mechanism; link members connecting between said yoke means and a vertically rotatably reciprocating arm; and a releasably constituted parallel link connecting between said crank and said arm.

12. In a device of the class described, the combination of: a polished rod; a head mounted upon said polished rod; yoke means supporting said head; reciprocative mechanism for rotating said head; a crank for reciprocating said mechanism; link members connecting between said yoke means and a vertically rotatably reciprocating arm; a parallel link connecting between said crank and said arm, said link containing releasing means adapted to render said link inoperative when resistance of rotated members against rotation exceeds a predetermined value.

In testimony whereof, I have hereunto set my hand at Los Angeles, California, this 6th day of April 1922.

SUMNER B. SARGENT.
